(57) **CLAIM**

The ornamental design for a charger for an X-ray digital imaging device as shown and described.

DESCRIPTION

FIG. 1 is a front perspective view of a charger for an X-ray digital imaging device, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view along line 8-8 in FIG. 2; and,

FIG. 9 is a cross-sectional view along line 9-9 in FIG. 6.

The broken lines shown in the drawings illustrate portions of the charger for an X-ray digital imaging device and form no part of the claimed design.

1 Claim, 9 Drawing Sheets
